DESIGN FOR A CABINET OR ENCLOSURE FOR FANS

Thomas Borth Jones, Webster Groves, Mo., assignor to Century Electric Co., St. Louis, Mo., a corporation of Missouri

Application July 15, 1933. Serial No. 48,721

Term of patent 7 years

To all whom it may concern:

Be it known that I, THOMAS BORTH JONES, a citizen of the United States and a resident of Webster Groves, county of St. Louis and State of Missouri, have invented a new, original, and ornamental Design for a Cabinet or Enclosure for Fans, of which the following is a specification, reference being had to the accompanying drawing, forming part thereof.

The figure is a perspective view of a cabinet, or enclosure for fans showing my new design.

The back of the cabinet or enclosure is characterized by a series of horizontally extending, vertically spaced strips which form slotted openings therebetween.

I claim:

The ornamental design for a cabinet or enclosure for fans, substantially as shown and described.

THOMAS BORTH JONES.
